UNITED STATES PATENT OFFICE.

HENRY B. PELTON, OF MISHAWAKA, INDIANA.

PAPER-ROLL PROTECTOR.

932,808.

Specification of Letters Patent. Patented Aug. 31, 1909.

Application filed April 17, 1909. Serial No. 490,637.

To all whom it may concern:

Be it known that I, HENRY B. PELTON, a citizen of the United States, residing at Mishawaka, in the county of St. Joseph and 5 State of Indiana, have invented certain new and useful Improvements in Paper-Roll Protectors, of which the following is a specification.

This invention relates to paper roll 10 protectors.

The object of the invention is to provide an article of this character which may readily and positively be secured in the mandrel-hole of a roll of any sheet material, and in 15 such manner as positively to preclude accidental disconnection, whereby to adapt the hole to constitute an efficient container for tacks, cleats and other articles used in the 20 positioning of sheet roofing, and further to insure the proper protection of the ends of the roll.

With the above and other objects in view, as will appear as the nature of the invention is better understood, the same consists in the 25 novel construction and combination of parts of a paper roll protector, as will be herein-after fully described and claimed.

In the accompanying drawings forming a part of this specification and in which like 30 characters of reference indicate corresponding parts—Figure 1 is a perspective detail view of one form of protector. Fig. 2 is a vertical longitudinal sectional view through a portion of a roll of sheet material, showing 35 the manner of assembling the protector therewith. Fig. 3 is a perspective detail view of the protector shown in Fig. 2. Fig. 4 is a vertical longitudinal sectional view 40 through a portion of a roll of sheet material, displaying a modified form of protector assembled therewith. Fig. 5 is a view in side elevation of a further modified form of protector. Fig. 6 is a sectional detail view of 45 a spreader used in connection with the protector shown in Fig. 5.

Referring to the drawings and to Figs. 1, 2 and 3 thereof, R designates a roll of sheet material of any character, and M the mandrel hole thereof. The protector consists of two parts, a ring or annulus, and a disk constituting a spreader and a roll end closure. The ring is struck up from a piece 50 of sheet metal, preferably one that is resil-

ient, and embodies an annulus 1 of a diameter approximating that of the roll, and a 55 plurality of fingers 2 integral with the walls of the central opening and disposed approximately at right angles to the annulus. The fingers terminate in arrow-head or triangular shaped heads 3, the wings of which 60 are bent at right angles to the length of the fingers to provide anchoring prongs 4, and the points 7 which are also bent at right angles to the length of the fingers but in a direction opposite the prongs to provide 65 stops 5 to limit the insertion of the spreader 6. Each finger is provided adjacent to the stop with a teat or spreader locking boss 7.

The spreader is constructed from a disk of 70 metal and is provided with a flange 8 disposed at right angles to the plane of the disk and furnished with notches 9 that enter the disk a distance equal to or somewhat greater than the lateral extent of the teats. The spreader is also provided with a pair of 75 spaced openings 10 to be engaged by a suitable tool to effect its turning to bring portions of the flange into locked relation with the teats.

To secure the end ring in place, the fingers 80 are first positioned within the mandrel opening with the annulus 1 resting against the end of the roll. The spreader is then inserted with the notches in line with the teats 7, and by a suitable implement is forced inward until checked by the stops 5. A key wrench is then inserted in the openings 10, and the spreader is turned to bring portions 85 of the flange 8 into locked engagement with the teats, thus securely fastening the former 90 in place.

In the form of invention shown in Fig. 4, the annulus 11 has its fingers 12 provided intermediate of their ends with pointed anchoring prongs 13, and its terminals bent to provide stops 14. The spreader 15 is a plain disk. The mode of positioning this form of 95 protector is the same as that above described.

In the form of invention shown in Figs. 5 and 6, the annulus 16 is provided with fingers 17 provided intermediate of their ends with pointed anchoring prongs 18 and with 100 terminal stops 19, the fingers being preferably normally disposed at an obtuse angle to the plane of the annulus to facilitate insertion into the mandrel hole. The spreader 105

20 is provided with an outward flared flange 21 to force the fingers outward and thus sink the prongs into the material of the roll.

Having thus described my invention, what 5 I claim is:—

1. A roll end protector comprising a ring having pronged fingers arranged to enter the roll and a spreader disk arranged to engage said fingers.

10 2. A roll end protector comprising a ring having pronged fingers arranged to enter the roll and a spreader disk forming a roll end closure.

15 3. A roll end protector comprising a ring having pronged fingers, a finger spreading disk and interengaging means on the fingers and disk.

4. A roll end protector comprising a ring having pronged fingers, inward extending projections on said fingers, and a closing disk 20 arranged to engage said projections.

5. In a roll end protecting and closing device, a ring having integral fingers provided with prongs, spaced projections adjacent the terminals of the fingers, and a disk 25 having marginal notches arranged to pass the outermost of said projections.

In testimony whereof I affix my signature, in presence of two witnesses.

HENRY B. PELTON.
